ELECTRICAL SWITCH HOUSING

Alan G. Eisenberg, Baltimore, Md.

Application February 8, 1957, Serial No. 44,805

Term of patent 14 years

(Cl. D26—13)

FIG. 1.

FIG. 2.

FIG. 3.

FIG. 4.

FIG. 5.

FIG. 6.

Fig. 1 is a perspective view of an electrical switch housing, showing my new design;

Fig. 2 is an elevation of one end thereof;

Fig. 3 is a side view of the front of the housing;

Fig. 4 is an elevation of the opposite end thereof;

Fig. 5 is an elevation of the rear of the housing, and

Fig. 6 is a top plan view thereof.

The dominant features of my new design are shown in solid lines in the drawing.

I claim:

The ornamental design for an electrical switch housing, as shown and described.
